BRACING FOR SCAFFOLDS AND THE LIKE

John A. Kirkpatrick, Zelienople, Pa., assignor to
Universal Manufacturing Corp., Zelienople,
Pa., a corporation of Pennsylvania

Application December 7, 1950, Serial No. 199,705

1 Claim. (Cl. 304—40)

1

This invention relates to the bracing of metal scaffolds, bleachers and the like, and more particularly to the braces and the brackets that detachably connect them to the legs of the structure being braced. For the sake of illustration this invention will be described as applied to metal scaffolds formed from spaced end panels that are connected by removable braces, but it is not limited thereto.

It is among the objects of this invention to provide such bracing in which the braces are moved horizontally into and out of position, in which the ends of the braces cannot rotate in a vertical plane on the legs they are bracing, in which the braces are retained in place by gravity-actuated locking members, and in which the supporting members for the braces are simple in construction and inexpensive to make and fasten to the legs.

According to this invention, horizontal pins of non-circular cross section, preferably rectangular, are rigidly connected to a pair of spaced vertical legs in such a manner as to project from the sides of the legs. For connecting the legs together a removable brace has end portions provided with openings for receiving the pins. Each of these openings is of substantially the same size and shape as the pins in cross section so as to keep the brace from rotating on the pins. By preventing the brace from rotating on the pins, the number of braces can be reduced. Thus, in a scaffold formed from end panels, only one brace need be provided at each side of the scaffold between any given pair of end panels. A movable locking member is supported by each brace-supporting pin and normally projects part way across the outer face of the adjoining end portion of the brace to hold the brace on the pin, but the locking member can be manually retracted to allow the brace to be removed from the pin. It is highly desirable that the locking member be gravity-actuated so that it will drop into locking position automatically. Preferably, it is a latch which is pivotally mounted in a vertical slot in the pin. When the outer end of the latch is swung upward the brace on the pin can be slid outward over the latch and pulled off the pin.

The preferred embodiment of the invention is illustrated in the accompanying drawings, in which Fig. 1 is a perspective view of a section of a scaffold provided with my bracing; Fig. 2 is an enlarged fragmentary view taken on the line II—II of Fig. 1, to show the end of one of the brace-supporting pins; Fig. 3 is a horizontal section through a leg, showing the pin from above;

and Fig. 4 is a combination side view and section of the pin taken on the line IV—IV of Fig. 3.

Referring to Fig. 1 of the drawings, each of a pair of vertical prefabricated scaffold end frames of any suitable construction has tubular legs 1 that may be rigidly connected by horizontal cross members 2 upon which wooden planking (not shown) may be placed to form a working platform. When the scaffold is assembled, the end frames are held upright by means of inclined side braces 3, and they may be further braced by crossed horizontal braces 4.

In order to detachably connect the ends of the braces to the scaffold legs, supporting pins 6 are fastened to each leg near its upper and lower ends. As shown in Fig. 2, each pin is non-circular in cross section, preferably being rectangular. The legs are provided with holes of the same shape as the pins for snugly receiving them. Each pin is inserted in a pair of holes in a leg with its opposite ends projecting therefrom, as shown in Figs. 3 and 4. One end projects only a short distance and is connected by a weld 7 to the leg to anchor the pin in it. The other end of the pin projects a much greater distance from the leg, most suitably from the inside of the leg, which is the side nearest to the other leg of the same frame. In this position the pins are more protected than if they projected from the outside of the legs.

The long projecting portion of each pin is provided with a vertical slot 8 that preferably extends entirely through it from top to bottom and inward from its outer end to a point close to the leg that supports the pin. Loosely disposed in the slot is a latch 9, the inner end of which is pivotally mounted on a rivet 10 extending across the inner end of the slot and having its heads countersunk in opposite sides of the pin so that they will not project beyond the surface of the pin. At no point is the vertical dimension of the latch greater than the height of the slot. It will be seen that the latch normally will swing down by gravity. The low inner corner of the latch strikes the inner end wall of the slot when the outer end of the latch has swung down a predetermined distance to its lower or locking position shown in Fig. 4. The bottom of the latch is provided with a two-sided notch 12, the upper wall of which is substantially horizontal when the latch is in its lower position. At that time the other wall of the notch is substantially vertical. This notch reduces the depth of a portion of the latch in such a manner that it can swing downward even though it is surrounded by the

end of a brace on the pin. The notch also forms a projection or nose 13 between the outer end of the notch and the outer end of the latch, which projects down from the bottom of the pin when the latch is in its lower position. The lower surface 14 of the nose is inclined from its lowest point outward and upward to the outer end of the latch in the pin slot for a purpose about to be described.

The braces 3 and 4 that are connected to the pins may be formed from members of any desired shape in cross section, but their ends should be provided with openings of substantially the same size and shape as the pins 6 in cross section. Each of the braces shown in the drawing happens to be formed from a length of pipe provided at its ends with vertical slots in which short metal plates 16 are welded. Each of these plates is provided with a rectangular opening 17 for more or less snugly receiving one of the rectangular pins. That is, the ends of the braces can be slid inward over the pins. This type of connection prevents the brace from rotating around the pins and thereby makes it feasible to use only one brace 3 at each side of the scaffold between each pair of panels. Of course, two or more braces can be used if desired. The pins project far enough from the legs to accommodate at least three braces per pin.

When the opening 17 in the end of a brace is lined up with one of the pins 6 and then the brace is pushed inward along the pin, the lower inclined surface 14 of the outer end of the latch is engaged by the bottom of the brace opening and is forced upward, thereby swinging the latch up into the pin. As soon as the end of the brace passes the latch nose 13, the latch will drop down again and the nose will form a lock that will hold the brace on the pin. When it is desired to remove the brace from the pin, the outer end of the latch is raised manually to the broken line position of Fig. 4 so that the brace can be pulled out along the latch and off the end of the pin.

It will be seen that in this bracing the braces are held on the brackets by latches that automatically swing down into locking position by gravity as soon as the braces are slid inward over them. The braces then can not be removed from the pins until the latches have been swung upward by hand into the pin slots. This locking mechanism is of simple construction and there is nothing about it to get out of order or to cause it to fail to operate automatically. No vertical movement of the braces is required in order to

mount them on the pins or to remove them therefrom. Consequently, if desired, the pins can be located close to the overlying horizontal cross members 2 of the end panels. A major advantage of this bracing is that it prevents relative rotation or tilting between the braces and legs in a vertical plane.

According to the provisions of the patent statutes, I have explained the principle of my invention and have illustrated and described what I now consider to represent its best embodiment. However, I desire to have it understood that, within the scope of the appended claim, the invention may be practiced otherwise than as specifically illustrated and described.

I claim:

A coupling for connecting a brace to a vertical leg, said coupling comprising a horizontal pin adapted to project from the side of said leg and extend through a hole in an end of said brace, the pin having a vertical slot in it, and a latch disposed in the slot with its inner end pivotally mounted therein, the latch having a depending projection at its outer end that extends below the pin to lock the brace thereon when the latch swings downward by gravity, the latch being provided with a surface adapted to engage the pin at the inner end of said slot to limit downward swinging of said projection, and the projection having a surface inclined from its bottom outward and upward to the pin to cause the projection to swing upward when a brace is pushed inward over the pin and against said inclined surface, the outer end of the latch being disposed in the slot when the latch is in its lower position.

JOHN A. KIRKPATRICK.
